UNITED STATES PATENT OFFICE.

WILLIAM J. BARR, OF BENNINGTON, VERMONT.

DESIGN FOR A PEDESTAL ASH TRAY.

Application filed February 1, 1928. Serial No. 25,121. Term of patent 3½ years.

To all whom it may concern:

Be it known that I, WILLIAM J. BARR, a citizen of the United States, and a resident of Bennington, county of Bennington, State of Vermont, have invented a new, original, and ornamental Design for a Pedestal Ash Tray, of which the following is a specification, reference being had to the accompanying drawing, forming a part thereof.

In the drawing:

I claim:

The ornamental design for a pedestal ash tray substantially as shown.

WILLIAM J. BARR.
